F. G. FOWLER.
PROCESS OF VULCANIZING RUBBER.

No. 439,137.

Patented Oct. 28, 1890.

UNITED STATES PATENT OFFICE.

FRANK G. FOWLER, OF BRIDGEPORT, CONNECTICUT.

PROCESS OF VULCANIZING RUBBER.

SPECIFICATION forming part of Letters Patent No. 439,187, dated October 28, 1890.
Application filed April 5, 1890. Serial No. 346,670. (No model.)

To all whom it may concern:

Be it known that I, FRANK G. FOWLER, of Bridgeport, in the State of Connecticut, and a citizen of said State, have invented a new and useful Improvement in the Process of Vulcanizing Rubber, of which the following is a specification.

The primary object of my invention is to vulcanize rubber goods uniformly. It also serves to prevent the formation of air-holes upon the surface of the goods vulcanized. It is useful where the process of vulcanizing is by steam heat, and particularly so where the steam is admitted direct into the receptacle which contains the articles to be vulcanized.

Notwithstanding vulcanization by the admission of steam direct to the articles to be cured is the most satisfactory and extensively used process, yet as heretofore practiced it is found that it cannot be accomplished uniformly, so that the goods will be homogeneous, and that while an article in one portion of the vulcanizer is properly cured in another portion it will be insufficiently cured and in another portion overcured, resulting in great loss and the production of inferior goods, which difficulties have baffled the skill of manufacturers up to the present time. My invention obviates these difficulties and renders the goods uniform and homogeneous throughout. It is founded upon a discovery which I will first explain, and then describe a form of apparatus by which it may be applied to use; but it must be understood that I do not limit myself to any form or arrangement of apparatus, since I believe my invention to be broader than any form of apparatus and to be capable of embodiment in a great variety of forms.

Water taken from a hydrant or well—such as is usually used for the purpose of supplying a boiler—holds in solution a large quantity of gases—such as oxygen, nitrogen, carbonic acid, ammonia, &c.—a great number of which may be held in solution at the same time. When water is evaporated from a boiler for the purpose of supplying a vulcanizer those gases are expelled from the water by the heat, and passed with the steam into the vulcanizer, where they remain as fixed gases, not condensing, as the steam does, when the temperature begins to lower. Herein consists the par-

ticular discovery to which I refer—namely, if a chamber be filled with part steam and part gas its temperature will not be uniform throughout, and the steam-gage will not always determine its temperature; but if such vessel is filled with steam only—and by "steam" I mean the vapor of water—its temperature will be uniform in every portion, and a steam-gage attached at one point will truly indicate the temperature of the chamber in every part, as the temperature will correspond with the steam-pressure.

My invention is founded on the discovery above outlined; and it consists substantially in removing the gases from the water before it is used to produce steam in the boiler and then passing the steam all freed from gases into the vulcanizer, whereby the same is provided with a perfectly-uniform temperature throughout, in every portion of it, during the process of vulcanization.

In the accompanying drawing I have shown by a diagram a general arrangement of apparatus by which my invention may be practiced.

a is a pipe for the feed-water, communicating with a well or hydrant.

b is a vessel in which the water and its gases are separated. The gases are drawn off through the pipe *c* by the air-pump *d*. The water runs off through the pipe *e* into a supply-tank *f*. Thence it is forced by the feed-pump *g* into the boiler *h*, arriving there freed from gases.

v represents the vulcanizing-chamber, and is provided with a cock *p* for blowing off the water of condensation.

i is a pipe connected to the boiler and communicating with the vulcanizer for the admission of steam for the purpose of curing the articles to be vulcanized.

k and *k'* is a pipe communicating between the vulcanizer and the receiver of the air-pump, by means of which the air can be exhausted from the vulcanizer.

I carry my invention into effect as follows: When the boiler *h* is first filled with water, the gases are removed from it by means of the air-pump *d*, which communicates with the boiler through the pipe *k*, and after that is done the gases are removed from the feed-

water in the vessel *b*, so that no more gases can enter the boiler. Steam may then be gotten up on the boiler *h*, and after the articles to be vulcanized are prepared and placed in the vulcanizer *v* it is closed, and the air removed from it by means of the pipe *k* and *k'*, which communicates between the vulcanizer and the receiver of the air-pump *d*. Steam is then admitted to the vulcanizer, and the air being already out it at once envelops all the articles to be vulcanized, so that they all start with the same degree of heat. As there is nothing admitted into the vulcanizer but the vapor of water, the heat is uniform and constant in all parts of the vulcanizer, and the goods are homogeneous and uniform when completed and their surfaces free from air-holes. A steam-gage attached to the vulcanizer indicates the exact temperature in all parts of the vulcanizer, and the attendant can thereby ascertain just how long the process should be continued to effect a proper cure. The air can be blown out in the ordinary manner through the cock *p*; but I prefer where great uniformity and homogeneousness are required to remove it by the air-pump.

The method of removing the gases from the water above described is the same as set forth in patents issued to me and numbered 346,198 and 377,099; but other methods may be used—for example, that described in Patent No. 423,423. This process can also be applied beneficially for the purpose of heating vulcanizing-presses or calender-rolls where the steam does not come in direct contact with the articles to be vulcanized.

I claim as my invention—

The process of vulcanizing rubber or other analogous substances, which consists in separating the gases from the water before it is used to produce steam and then passing the steam all freed from gaseous substances into the vulcanizer, whereby the same is maintained at a uniform temperature in all its parts during the process of vulcanization and the goods cured alike and rendered homogeneous in quality, substantially as set forth.

FRANK G. FOWLER.
